(57) CLAIM

The ornamental design for a display screen with icon, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a front view of a display screen with icon showing my new design; and,

FIG. 2 is a front view of a display screen with icon showing an alternative embodiment of my new design.

The broken line showing of the remainder of the user interface and the remainder of the display screen is for environmental purposes only and forms no part of the claimed design.

1 Claim, 2 Drawing Sheets

(2 of 2 Drawing Sheet(s) Filed in Color)
